(57) **CLAIM**

The ornamental design for an electronic calculator as shown and described.

DESCRIPTION

FIG. 1 is a reduced-scale front, left side perspective view of an electronic calculator of the first embodiment showing our new design;

FIG. 2 is a front elevational view of the first embodiment thereof;

FIG. 3 is a rear elevational view of the first embodiment thereof;

FIG. 4 is a left side view of the first embodiment thereof;

FIG. 5 is a right side view of the thereof;

FIG. 6 is a top plan view of the first embodiment thereof;

FIG. 7 is a bottom plan view of the first embodiment thereof;

FIG. 8 is a reduced-scale front, left side perspective view of an electronic calculator of the second embodiment showing our new design;

FIG. 9 is a front elevational view of the second embodiment thereof;

FIG. 10 is a rear elevational view of the second embodiment thereof;

FIG. 11 is a left side view of the second embodiment thereof;

FIG. 12 is a right side view of the second embodiment thereof;

FIG. 13 is a top plan view of the second embodiment thereof; and,

FIG. 14 is a bottom plan view of the second embodiment thereof.
